FIG. 18

MACHINE FOR DIGGING UNDERGROUND GALLERIES

The present invention relates to a machine for digging underground galleries, comprising a framework displaceable in the gallery, at least a pair of homologous arms connected to this framework and adapted for swinging movements respectively about two substantially parallel axis, a toolholder on each arm and cutting tools on each toolholder, adapted to cut through a cutting face of the gallery.

Machines of this type present the advantage of allowing the digging of galleries having substantially a rectangular cross section. The edges of this section, which are perpendicular to the swinging axis of the homologous arms, are substantially linear.

Throughout the present specification, the terms "floor and roof of the gallery" designate both walls of the same, corresponding to these substantially linear edges of the cross section of the gallery.

In known machines of this type, the position of the toolholders on the pair of homologous arms and the respective positions of these arms on the framework allow only a swinging movement of each arm of about 90°, from a position in which it is directed towards a lateral wall of the gallery as far as a position in which it is substantially parallel to the gallery's axial plane, and vice-versa.

With such a machine however, the tools of each toolholder are able to cut through the cutting face of the gallery only as they are swung from a lateral wall towards the axial plane of the gallery. This can be disadvantageous in case of cutting galleries through lightly cohesive formation, while it can occur the dislodging, from the central area of the cutting face, of blocks of rocks of excessive sizes, which are difficult to remove.

Further, in case of cutting through hard rocks, the beginning of the cutting operation from lateral walls is particularly difficult.

The object of this invention is to avoid this difficulty and to provide a machine which is further of a much greater efficiency.

For this purpose, in the machine according to the invention, each of the homologous arms and the position on the latter of its toolholder are adapted for a swinging movement of this arm greater than 90° from a position in which the arm is directed towards a lateral wall of the gallery as far as a position in which the arm is directed towards the other lateral wall, whilst passing through a position in which the arm is parallel to the gallery's axial plane, the cutting tools passing continuously along the cutting face of the gallery.

In the machine according to the invention, the swinging movement of each arm corresponds, for example, to 120° to 250°. Under the action of the forces to which the cutting tools are subject during the swinging movements of the arms, these cutting tools act on the cutting face and from the latter cut a crescent-shaped rock "chip" which disintegrates in step with its formation.

In the case in which the machine is driven forward in the gallery in such manner that the swinging axis are parallel to the vertical plane passing through the axis of the gallery, the roof and floor of the gallery will extend along two horizontal lines in cross section, which evidently facilitates the placing in position of the timbering and the laying of a rolling or rail track.

It is obviously possible to drive the machine forward in such manner that the swinging axis are oblique relative to the vertical plane passing through the axis of the gallery. This arrangement of the machine according to the invention may be useful for digging a gallery through a geological stratum, without impairing the integrity of at least one wall or delimitation of this geological stratum.

In the machine according to the invention, it is possible to turn sufficiently each arm towards any one lateral wall of the gallery for its toolholder being no more in contact with the cutting face of the gallery.

It is thus possible, with the machine of this invention, to displace forward the framework, towards this cutting face, even as homologous arms are directed towards the central plane of the framework.

5 The machine according to the invention is thus adapted for the toolholders cutting through the cutting face from the central part of this cutting face, as far as the lateral walls of the gallery, which avoids the disadvantages mentioned hereabove for machines of the prior art.

10 Throughout the specification, the expression "operational cycle of a toolholder" relates to the displacement of the toolholder, from a first position in which its arm is directed towards a lateral wall of the gallery, as far as a second position in which this arm is directed towards the other lateral wall of the gallery and the going back as far as the first position, the toolholder passing continuously along the cutting face of the gallery between these two positions.

15 The working of the machine may thus be regulated for each toolholder cuts in the cutting face, only during one half of its operational cycle, for example during its displacement by the arm whereon it is carried, from the aforesaid first position as far as the aforesaid second position of this operational cycle. During the other half of its operational cycle, the toolholder does not act on the cutting face.

20 The working of the machine may thus be regulated for each toolholder cuts in the cutting face, only during one half of its operational cycle, for example during its displacement by the arm whereon it is carried, from the aforesaid first position as far as the aforesaid second position of this operational cycle. During the other half of its operational cycle, the toolholder does not act on the cutting face.

25 The working of the machine may thus be regulated for each toolholder cuts in the cutting face, only during one half of its operational cycle, for example during its displacement by the arm whereon it is carried, from the aforesaid first position as far as the aforesaid second position of this operational cycle. During the other half of its operational cycle, the toolholder does not act on the cutting face.

30 In case of a working of this kind for the machine, it is only after the toolholders have carried out a complete operational cycle, that the arms may be displaced towards the cutting face on a distance equal to the forward step chosen, i.e. on a distance equal to the maximum thickness of the rock "chip" which is to be cut through the cutting face of the gallery. This forward step may be chosen before each forward displacement of the arms according to the actual rock cutting resistance.

35 The working of the machine may also be regulated so that each toolholder cuts through the cutting face during both parts of its operational cycle, i.e. on the one hand, during its displacement by the arm whereon it is carried, from the first position as far as the second position and, on the other hand while it comes back from this second position as far as the first position.

40 In case of a working of this kind for the machine, the arms are to be moved forward in the gallery, on a distance equal to the forward step chosen, after each half of an operational cycle.

45 In the machine according to the invention, the cutting tools may be, for example, picks, rotatable cutters, compressed air tools, hydraulic or pyrometric means, or any other tools adapted to cut through a cutting face of a gallery. Each toolholder may be fixed or rotative on its arm.

50 According to a particular embodiment of the machine of this invention, in case of each tool holder is a rotatable toolholder, the latter can be mounted on its arm with its rotation axis substantially parallel to an axial plane of the arm. With such an embodiment, it is possible to arrange the cutting tools on each toolholder for these tools acting on the cutting face of the gallery approximately tangentially to their courses about the swinging axis of the arm of this toolholder. In this embodiment, it is particularly advantageous to use as cutting tools, cutting discs having one or more discs. Cutting discs are further usually more appropriate for digging in hard rock. In this embodiment, the forces required to drive the toolholders, all other conditions being identical moreover, are very much

55 smaller than those needed to drive the toolholders of the known machines, which frontally act on the cutting face. Another advantage of this embodiment resides in the fact that no minimum number of cutting tools is mandatory.

60 All other things being equal, it is possible for this machine to require less power. As a result, it is less bulky, less heavy and consequently easier to handle.

65 In this particular embodiment of the machine of this invention, if the cutting tools are cutters of the single disc type, it is advantageous for these to be arranged in two or more stepped areas on each tool holder and it is possible to establish the op-

timum offset of the tools on the toolholder. This advantageous feature of this embodiment resides in the fact that, in this case, the tool holders act approximately tangentially on the cutting face and work along a narrow "pass" or cut. The removal of the waste or rubble is thus facilitated and directional control over the tool holders within the gallery is easier.

The optimum stepped or offset pattern of the cutters depends on the nature of the rock and the machine is advantageously contrived in such manner that this offset is adjustable.

Beyond the advantages cited hereinabove, the machine according to the invention greatly facilitates access to a tool holder, for example to replace a cutting tool of the same, without having to reverse the machine in the gallery. In this point of fact, it may be arranged in such a manner that the arms carrying the toolholders may be sufficiently turned alongside the sidewalls of the gallery, in such manner as to allow a removal and replacement of a tool. To facilitate access to the toolholders, it is advantageous to build the machine in such manner as to contrive convenient passages between the framework of the machine and the lateral walls of the gallery. These passages may moreover be useful for the placing in position of the timbering, at a short distance from the cutting face.

As it is designed to the digging of broad galleries, the machine according to the invention may comprise more than a pair of homologous arms adapted to swing respectively about two parallel swinging axis. According to the breadth of the gallery to be dug, the machine may comprise, for example, three, four or more homologous arms adapted to swing respectively about three, four or more parallel swinging axis.

Moreover, according to the height of the gallery to be dug, the machine according to the invention may comprise more than one arm — for example two or three superposed arms — able to swing about each swinging axis. It is thus possible with the machine of this invention to cut galleries of great cross-section by means of toolholders of small size, thereby reducing the stresses on each toolholder to a large extent.

In the case of a machine comprising more than one arm able to swing about each swinging axis, each arm may be mounted on a rotatable turret the axis of which is the swinging axis. The turrets of the superposed arms able to swing about each swinging axis may thus be individually displaced, for example by means of individual motors.

In the case of a machine having at least two superposed arms able to swing about each swinging axis and the superposed arms having to be displaced simultaneously about this swinging axis, it can be advantageous to fix these superposed arms on a common pillar of which a longitudinal axis is the swinging axis.

Each pillar may be mounted on the carriage for the latter being able to pivot about this pillar.

The invention relates also to a process for cutting underground galleries by using a machine according to the invention. This process comprises making each arm of the machine execute successive operational cycles.

The process according to the invention comprises further, after having made one arm or a group of superposed arms able to swing about a common swinging axis, to execute a complete operational cycle — respectively one half of an operational cycle — and before making the arm or group of superposed arms to execute a further complete operational cycle — respectively the other half of an operational cycle —, moving forward the arm or group of superposed arms towards the cutting face of the gallery, for a distance substantially equal to a forward step chosen, the next swinging axis being maintained stationary until the arm or the group of superposed arms of this last swinging axis have completed a complete operational cycle — respectively one half of an operational cycle.

In this process, the forward step may be advantageously chosen, before each forward movement of an arm or a group of superposed arms, according to the actual rock cutting resistance.

Features and details of the invention will emerge from the following description and accompanying drawings, which diagrammatically and by way of example only, illustrate some examples of the machine according to the invention and of its working.

FIG. 1 is a diagrammatical plan view, partially sectioned, of a first form of embodiment of the machine according to the invention, whose toolholders act on the cutting face of a horizontal gallery in process of being cut, seen in section;

FIG. 2 is a side view of the embodiment of FIG. 1;

FIG. 3 is a front view of a toolholder of the machine of FIGS. 1 and 2;

FIG. 4 is a side view of the toolholder illustrated in FIG. 3;

FIG. 5 is a partial diagrammatical horizontal section through the cutting face of the gallery, this cutting face being acted upon by two cutting tools of the toolholder of FIGS. 3 and 4;

FIG. 6 is a partial side view of a particular fixing of a tool on a toolholder;

FIG. 7 is a diagrammatical plan view illustrating respective sizes of an advantageous modified form of the machine of this invention;

FIG. 8 shows in front view, toolholders of two superposed arms able to swing about a common swinging axis on the machine according to the invention, these toolholders being coupled to one another by a torque transmission device;

FIG. 9 is a plan view of a evacuating device of rubble cuts, equipping the machine illustrated in FIGS. 1 and 2;

FIG. 10 is a front view of the cutting face of the gallery cut by means of the machine illustrated in FIGS. 1 and 2;

FIG. 11 is a section through a geological stratum traversed by a gallery cut by means of the machine of FIGS. 1 and 2;

FIG. 12 is a diagrammatical plan view, partially sectioned, of a second form of embodiment of the machine according to the invention, whose toolholders act upon the cutting face of a gallery in process of being cut,

FIG. 13 is a side view, partially sectioned, of the embodiment of FIG. 12;

FIG. 14 shows in plan view, the machine of FIGS. 12 and 13, adapted for a particular type of working;

FIG. 15 shows in plan view, the machine of FIGS. 12 and 13, adapted for another type of working;

FIGS. 16 and 17 are diagrammatical plan views of a machine similar to that of FIGS. 11 and 12, respectively in two successive positions of the said machine during the cutting of the cutting face of the gallery according to a particular type of working;

FIG. 18 is a plan view, partially sectioned, of a third embodiment of the machine according to the invention, whose toolholders act on the cutting face of a horizontal gallery in process of being cut, seen in section,

FIG. 19 is a partial plan view, partially sectioned, of a fourth embodiment of the machine according to the invention, whose toolholders act on the cutting face of a horizontal gallery in process of being cut, seen in section.

In these figures, the same referential notations denote identical elements.

In a first form of embodiment, shown on FIGS. 1 and 2, the machine comprises a framework 1 on which a carriage 2 is slidabile. The framework 1 is equipped with four pairs of jacks 3 which are intended to immobilize the framework 1 in a gallery 4 in process of being cut, whilst bearing against the roof 5 and the floor 6 of this gallery.

At the front, the carriage 2 is equipped with two lower bearers 7 intended to uphold the same on the floor 6 and with two upper jacks 8 intended to immobilize the same in the gallery 4, whilst bearing against the roof 5 of the latter. At the rear, the carriage 2 is equipped with two pairs of jacks 9 intended to enhance its immobilization in the gallery 4, whilst bearing against the roof 5 and the floor 6 of the gallery, for this purpose.

The framework 1 and the carriage 2 are connected by means of four jacks 10 which are articulated each at their two ends.

Carriage 2 carries two vertical pillars 36, 36', which are in prolongation of the bearers 7 and jacks 8. Two superposed arms 11 are arranged on the pillar 36 about which they can swing; two similar superposed arms 12 are arranged on the pillar 36' about which they can swing. Each arm 11 carries a toolholder 16 provided with cutting tools 20; similarly each arm 12 carries a similar toolholder 17. The toolholders 16 and 17 are rotatable toolholders and are each mounted at the extremity of their arm 11 and 12 with their rotation axis substantially parallel to this arm. Thus, each toolholder continuously faces substantially the wall of the gallery towards which its arm is directed.

The cutting tools 20 are rotatable cutters of the single-disc type. There are six of these per toolholder. They are preferably disposed on each toolholder for approximately facing the cutting face of the gallery. Each cutting disc 20 is thus approximately tangential to its course about the swinging axis of the arm of its toolholder.

The position of the arms 11 and 12, on the aforesaid pillars 36, 36' is such that by rotation around the axis of these pillars, these arms are entrained from a position in which the toolholders 16 of arms 11 substantially face the toolholders 17 of homologous arms 12, as far as a position in which these toolholders 16 and 17 substantially face the side walls 22 and 23 of the gallery 4, and vice-versa. During this rotation or swinging movement of the arms, the latter are passing through a position in which the toolholders are directed towards the forward part of the machine and the cutting face 24 of the gallery. The entrainment of the arms is arranged to be performed, for example, by means of jacks, or of an electric or fluidic motor.

During this rotation of the arms 11 and 12, the toolholders 16 and 17, are in rotation and the cutting discs 20 progressively act tangentially on the cutting face 24 of the gallery in four contiguous areas 25 and 26 having the form of spherical segments (FIG. 7). Between these spherical segments, the cutting face 24 has three spurs 29, 30 and 31 extending in the direction towards the entrance of the gallery 4 and along the axial plane of this gallery (FIG. 10). It is necessary to demolish the spurs which would otherwise impede the progress of the machine in the gallery 4. For this purpose, the carriage 2 carries three rock drills 32 at the level of the floor 6 and three analogous rock drills 32 at the level of the roof 5. These drills are impelled pneumatically for example, and are intended to cut the upper spur 29 along the roof 5 and the lower spur 31 along the floor. The carriage 2 is further equipped with core-brakers (not illustrated) in the form of a wedge or chisel. Under the action of the advance of the carriage 2 in the gallery, these core-brakers exert a lateral force on the spurs 29 and 31 which finally break off.

It is evident that other means could be used for demolishing these spurs 29, 30 and 31.

The machine illustrated in FIGS. 1 and 2 will operate according to the following working cycle: the jacks 3 of the framework 1 are wedged against the roof 5 and the floor 6 of the gallery 4. The carriage 2 whose jacks 8 and 9 are retracted, is displaced towards the cutting face 24 by means of the jacks 10 along a distance equal to the cutting step scheduled. At the same time, the toolholders 16 and 17, begin to be entrained around their corresponding swinging axis, so that the cutting discs 20 of the toolholders begin to act on the cutting face 24 substantially tangentially. When the carriage 2 has been displaced by a cutting step distance (illustrated at 47 in FIG. 5), it is immobilized in the gallery by means of the jacks 8 and 9. The arms 11 and 12, are then entrained around the pillars 36, 36', from a position in which the toolholders 16 face substantially the toolholders 17, as far as a position in which these toolholders are substantially face to face with the side walls 22 and 23 of the gallery. During this rotation of the arms around the pillars and of the toolholders around their corresponding rotation axis, the cutting discs 20 of each toolholder cut a crescent-shaped rock "chip" from the cutting face 24.

After this rotation of the arms, which can advantageously amount to close to 210°, they are returned without cutting action to their initial starting position.

As the carriage 2 has been moved away from the framework 1, for a maximum distance allowed by the jacks 10, the jacks 3 of the framework 1 are released during the rotation of the arms 11 and 12, for their return to the initial starting position and this framework 1 is displaced towards the cutting face 24 by means of the jacks 10, along a distance equal to the broke of jacks 10. The jacks 3 are then wedged again against the roof 5 and the floor 6 of the gallery and the jacks 8 and 9 of the carriage 2 are freed. The machine is then ready to begin another working cycle.

It is easy to gain access to the tool holders 16 and 17, in the machine illustrated in FIGS. 1 and 2. In point of fact, by rotation of the arms 11 and 12, it is possible to bring these toolholders close to the side walls 22 and 23 of the gallery 4, in such manner as it can be possible to replace a faulty cutting disc. An operator can then easily pass between the machine and a side wall of the gallery to reach a toolholder.

The choice of the direction of cutting from the center of the gallery towards the walls, and the fact of omitting to exploit a working stroke in the opposite direction, are dictated by the fact that along the intersection of two adjacent cuts 25, 26, the cutting face 24 of the gallery presents two free faces which make very much easier the cutting in the rock than the beginning from the lateral walls 22 and 23. Further, such a proceeding eliminates any risk of an uncontrolled stripping of the rock in a protrusion zone which is thus particularly brittle.

If the nature of the rock were to be such that difficulties of this kind need not be feared, it is obviously permissible to perform a cutting action also whilst turning from the sides towards the center of the gallery, and to work alternately in the two directions.

FIGS. 3, 4, 5 and 6 show particularly advantageous embodiments of a tool holder with its cutting discs 20. The cutting discs are situated in the peripheral part of the toolholder. They are contingently distributed in two stepped areas, each comprising three cutting discs. They are grouped moreover in three groups 15 of two cutting discs, each group comprising one cutting disc from each of the two aforesaid stepped areas. Relative to the direction of rotation X of the toolholder, the cutting disc of the outer area of each group precedes the cutting disc on the inner area (see FIG. 3). Relative to the direction of advance Y of the machine in the gallery, the cutting discs of the inner area (shown in thick lines in FIG. 5) are slightly ahead of the cutting discs of the outer area (shown in thin lines in FIG. 5). This stepping of the cutting discs 20 in two areas facilitates the cutting operation without impairing the extraction of the rubble.

To facilitate the action of the cutting discs 20 on the cutting face, it proved to be preferable to install these on their toolholder in such manner that their corresponding axis of rotation constitute substantially generatrix of a conical surface whose axis coincides approximately with the axis of rotation of the toolholder.

For providing an adequate clearance angle of each cutting disc on the cutting face of the gallery, the apex of this conical surface is, with respect to this cutting face, beyond the swinging axis of the arm carrying the toolholder of the cutting disc.

It was observed that for both discs of each group 15, the optimum spacing of the discs parallel to the direction of advance Y of the machine depends on the nature of the rock. To allow the adaptation of this spacing to the nature of the rock, the cases 21 wherein are engaged the shafts of the tools 20 (FIG. 4) are inserted into corresponding hollow casings of the toolholders and metal plates of definite thickness are placed in the bottom of these casings so that the penetration of these cases into these casings may be adjusted at will. Another adjusting device for example screws, may be employed instead of these metal plates.

It was also observed that, generally, for both cutting discs of each group 15, the optimum ratio between the spacing parallel to the Y-direction and the spacing transverse to this direction is constant, whatever may be the spacing parallel to the Y-direction. According to a particular form of embodiment shown on FIG. 6, the hollow casing 56 wherein the case 21 of

each cutting tool 20 is inserted, is removably engaged into a corresponding recess 58 of the toolholder. This recess 58 comprises along each radial side, a face 57 which is inclined at substantially 45 degrees with respect to the rotation axis of the toolholder, towards the peripheral part of the machine. The casing 56 is provided with two flanges 59 adapted to cooperate with the inclined faces 57. Teeths or ribs are advantageously provided on the flanges 59 and through faces 57 for reinforcing the fixation of the casing 56 in recess 58. This fixation can be ensured by means of bolts 60. As hereinbefore explained, the position of the case 21 in the casing 56 may be regulated by plates 61 of definite thickness, placed in the bottom of this casing 56.

In front of each group 15 of two cutters 20, the toolholders are each equipped with finishing picks 33 and with oblique scrapers 34. The picks 33 are intended to plane the surface of the cutting face, to make the same more uniform. The scrapers 34 form protective screens for the two cutting discs 20 they precede, against waste dislodged by the cutting discs 20 preceding these screens and thrown rearwards.

Moreover, at the level of the floor 6, the scrapers 34 of the two lower toolholders 16 and 17 are employed to impel the waste cut into two circular bins 35 (FIGS. 2, 4 and 8) arranged on the floor, respectively around the two aforesaid pillars 36, 36'. These circular bins 35, at their periphery, have a sloping plane 37 intended to allow the waste impelled by the scrapers 34 to pass from the floor 6 into the bins 35.

In each of the bins 35 is arranged a scraping tool 38 arranged on a sleeve 39 surrounding the pillar 36 or 36' corresponding to this bin. It is imparted to the scraping tool 38 a reciprocating rotary motion around the pillar, in such manner as to impel the waste contained in its bin 35 towards a conveyor 40 over two ramps 41 and 42 disposed respectively in prolongation of the conveyor 40 and transversely to this conveyor.

The conveyors 40 (for example drag conveyors) propel the waste on to an axial conveyor 43 which evacuates these to the entrance of the gallery 4. This axial conveyor 43 is a conveyor belt, for example.

It is advantageous to co-ordinate the machine according to the invention with an auxiliary framework 44 situated behind the framework 1 of the machine. This auxiliary framework (partially illustrated in FIGS. 1 and 2) is equipped with four pairs of jacks 45 (of which two pairs only are apparent in the Figures) intended to immobilize the same in the gallery 4 by bearing, for this purpose, against the roof 5 and the floor 6 of the gallery 4.

A jack 46 connects the auxiliary framework to the carriage 2 (FIG. 1).

In particular, the auxiliary framework is intended to carry facilities which are not essential on the framework 1 and the carriage 2 (for example tanks containing the fluid for operation of the jacks, pumps, an electrical transformer, etc.). Thanks to this fact, it is possible to reduce the bulk of the framework 1 and of the carriage 2 in substantial manner, in particular to shorten these two elements, in such manner as to allow of a rotation of the assembly of the framework and carriage in the gallery, for the purpose of starting another gallery directed differently.

For rotating framework 1 and carriage 2 as a whole in the gallery, for example around pillar 36', the framework 1 is brought as close together with the carriage 2, to reduce the floor area of the machine to a minimum. The jacks 45 are wedged against the roof and floor of the gallery 4 to immobilize the auxiliary framework 44 therein. The jacks 3 of the framework 1 are released, as well as the jacks 9 of the carriage 2 and the jack 8 of this carriage, corresponding to pillar 36. Framework 1 and carriage 2 are then rotated inside the gallery by means of the jack 46, around the pillar 36', the jack 8 of this pillar being maintained wedged against the roof 5 of the gallery 4.

As explained hereabove, thanks to the presence of the auxiliary framework 44 behind the framework 1, it is possible to

reduce considerably the bulk of the framework 1 and carriage 2. According to a particular feature of the machine, in each plane perpendicular to both swinging axis of arms 11 and 12, the maximum distance a (FIG. 7) between the rotation axis *b* about which framework 1 and carriage 2 are rotated (which can be the axis of pillars 36, 36') and the periphery of framework 1, is lower than the distance *c* between the rotation axis *b* and the longitudinal axial plane of this framework 1, plus the distance *d* between each swinging axis and the longitudinal plane, plus the distance *e* between each swinging axis and the periphery of the toolholder of the arm of the swinging axis.

With such an advantageous embodiment, it is possible to rotate the assembly of framework 1 and carriage 2 inside the gallery, for starting another gallery which can be directed at right angle or even more.

To modify the gradient of a gallery in process of being cut, the jacks 8 of the carriage 2 are released, and the assembly of the framework 1 and carriage 2 is pivoted around bearers 7, by means of the jacks 9 of the carriage 2, and/or by means of the jacks 3 of the framework 1.

The auxiliary framework 44 may also be used for making the machine to pivot around both bearers 7 in view of modifying the gradient of the gallery. For this end, jacks 45 of this auxiliary framework are wedged against floor and roof of the gallery 4 and all jacks 3, 8 and 9 of framework 1 and carriage 2 are released. The aggregate of the framework 1 and carriage 2 is then pivoted as a whole around both bearers 7, by means of the jack 46.

For allowing the aforesaid rotation around one or both bearers 7, it is preferable to connect each bearer 7 to the carriage 2 by an articulation means (not shown).

The auxiliary framework 44 moreover represents a safety element for immobilization of the machine in the case of cutting a gallery of considerable gradient.

In the proceeding description, the auxiliary framework 44 has been supposed to be connected to the carriage 2. While this disposition is preferable for reason of safety, it is well evident that this auxiliary framework 44 could be connected to the framework 1.

In the case of the machine hereabove described used with its pillars 36, 36' continuously parallel to a vertical plane, the gallery cut has a vertical symmetry plane. In this case, the roof 5 and the floor 6 of the gallery correspond to two horizontal lines, in cross section.

It is evident that this is equally applicable to cut a gallery having an oblique symmetry plane. This may be advantageous if it is intended to cut a gallery through a geological stratum, without cutting the roof or hanging wall. An analogous case has been illustrated in FIG. 10.

In the machine hereabove described and shown on FIGS. 1 and 2, the arrangement of the arms 11 and 12 on the pillars 36, 36' may be contrived in such manner that these pillars are stationary and that the arms turn around these. Provision may equally be made for the case in which the arms are keyed on the pillars which are then entrained in rotation around their corresponding axis.

In a modified form of embodiment, each arm 11, 12 is integral with a turret which is mounted on the carriage for swinging movement.

In another modified form of embodiment, both superposed arms 11 or 12 able to swing about a common swinging axis are adapted for pivoting about this swinging axis in opposite directions, while remaining continuously in symmetrical positions. With such an embodiment, a good counterbalancing of the machine is obtained. In such a machine, both superposed arms of each swinging axis or respective motors of these superposed arms are for example, connected to one another by a synchronization transmission device known per se, adapted to maintain continuously both superposed arms in symmetrical positions.

In case of both superposed arms able to swing about each swinging axis are stationary to one another (for example in

case of these arms are keyed on their pillars 36 or 36'), it is preferable these superposed arms being parallel to one another. In case of these two superposed arms are provided with toolholders as shown on FIGS. 3 and 4 and described hereabove, it is advantageous that both toolholders rotate in opposite directions. Moreover, according to the disposition of the cutting tools or discs 20 on each toolholder, the resistant torque opposed to the rotation of this toolholder by the cutting face 24 varies according to the angular position of this toolholder about its rotation axis. It is thus advantageous to couple both superposed toolholders to one another as being in well definite position with respect to one another, so that as the resistant torque of one of both toolholders is maximum, the resistant torque of the other one is minimum.

Such a coupling of both superposed toolholders is also advantageous in case of one of these toolholders acts on a rock the hardness of which is different from the hardness of the rock on which the other toolholder acts.

A motor such as an electric or fluidic motor for the simultaneous rotation of both toolholders can thus function with an optimum efficiency.

FIG. 8 shows a coupling device of two toolholders similar to that of FIG. 3. This coupling device includes a gear 62 on a first toolholder and a free gear 63 meshing with gear 62. On gear 63 is coaxially fixed another gear 64 meshing with a chain 65 passing on a gear 66 coaxially fixed on a second toolholder.

FIGS. 12 and 13, show a particular form of embodiment of the machine of this invention.

As the embodiment of FIGS. 1 and 2, the machine of FIGS. 12 and 13 comprises a framework 1 and a single carriage 2. This carriage 2 carries two parallel pillars 36, 36' about each of which two arms can swing, i.e. arms 11 with toolholders 16 for pillar 36 and arms 12 with toolholders 17 for pillar 36'. In prolongation of each pillar 36, 36' the carriage 2 is provided with a forward lower bearer 7 and a jack 8. The carriage 2 is further provided with two rearward lower bearers 48, as well as with a pair of jacks 49 adapted to be applied respectively against the lateral walls 22 and 23 of the gallery, in view of immobilizing the carriage.

Both pillars 36, 36' are connected to the carriage 2 for allowing a rotation of this carriage about any one of these pillars. For this end, bearings are preferably interposed between carriage 2 and each pillar 36, 36'.

The toolholders 16 and 17 and the tools 20 are advantageously similar to those described hereabove in case of the machine of FIGS. 1 and 2.

The machine of FIGS. 12 and 13 is different from the machine of FIGS. 1 and 2 by the fact that the carriage 2 is not slideable on the framework 1, to which it is however connected by four articulated jacks 10.

Another difference of the machine of FIGS. 12 and 13 with the machine of FIGS. 1 and 2 is in the dimensions and the relative positions of the arms 11 and 12. In the machine of FIGS. 12 and 13, the length of the arms 11 and 12 is greater than the half of the distance between the axis of both pillars 36 and 36'. Thus, the areas 25 having the form of spherical segments, cut in the cutting face 24 by the toolholders 16 partially overlap the homologous areas 26, cut in the cutting face 24 by the toolholders 17. With such a machine, the spurs 29, 30 and 31 between areas 25 and 26 are suppressed, so that means such as rock drills are not necessary for the demolishing of these spurs.

For allowing the rotation of the arms 11 and 12 around pillars 36 and 36', the position of the superposed arms 11 is asymmetrical with the position of the superposed arms 12, with reference to the machine's axial plane.

For this purpose, the superposed arms 11 may be coupled to the superposed arms 12 by a synchronization torque transmission device maintaining continuously arms 11 substantially parallel to arms 12 during their operational cycle as defined hereabove.

FIG. 14 shows such a particular form of the embodiment of FIGS. 12 and 13.

With such a particular form of the machine, the cutting through the cutting face may generally be made so that as one of two homologous arms 11 and 12 acts against the cutting face 24 while swinging from outside towards inside, the other one acts against this face 24 while swinging from inside towards outside. Each arm 11, 12 acts thus on the cutting face during both half of its operational cycle and the carriage 2 is moved forward after each half cycle for advancing simultaneously both pillars 36 and 36' towards the cutting face on a distance equal to the cutting step. For the counterbalancing of the machine, it is advantageous that both superposed arms 11 and both superposed arms 12 be coupled to one another by a synchronization torque transmission device ensuring swinging movements in counter directions of both superposed arms mounted on each pillar. Thus, as one arm 11 rotates from outside towards inside, the other arm 11 rotates from inside towards outside, each arm 12 remaining parallel to the next homologous arm 11.

According to another particular form (shown on FIG. 15) of the embodiment of FIGS. 12 and 13, the superposed arms 11 are coupled to the superposed arms 12 by a torque transmission device which is adapted for superposed arms 11 assuming positions substantially symmetrical with superposed arms 12 during a portion of the first half of their operational cycle, as they are moved from outside towards inside. Near their junction point, arms 11 are stopped (as in position shown on FIG. 15) while arms 12 end the first half of their operational cycle and begin the second half of this cycle. After these arms 12 have moved on a sufficient portion of the second half of their operational cycle, the arms 11 are moved again for ending their entire operational cycle.

Such a form of embodiment is interesting for the counterbalancing of the machine.

As explained hereabove, it is advantageous to begin a new cut along the intersection of two adjacent cuts 25, 26 because the cutting face 24 of the gallery presents there two free faces which make very much easier the cutting in the rock than the beginning from the lateral walls and also because such a proceeding eliminates any risk of an uncontrolled stripping of the rock in a protrusion zone which is thus particularly brittle.

In view of allowing such a cutting of the cutting face 24 with the machine of FIGS. 12 and 13 in particular when arranged as shown on FIG. 15, without having too serious difficulties in the construction of the machine and also in view of avoiding any pause during the working of the tools, the inventor has proposed to move forward separately both pillars 36 and 36' on a distance equal to the forward step chosen.

This process according to the invention for digging a gallery 4 by means of the machine of FIGS. 12 and 13 will be more understood from the following description.

The case will first be considered, for which the toolholders 16 and 17 act on the cutting face 24 of the gallery 4, only during one half of their operational cycle as defined hereabove, i.e. whilst they are displaced from the central zone of gallery 4 as far as the lateral walls 22 and 23 of the gallery, the toolholders passing continuously along the cutting face 24.

According to this process, after the toolholders 17 have ended an operational cycle and before they begin a further operational cycle, the carriage 2 is pivoted around the pillar 36 carrying the superposed arms 11, in sense of the arrow A (FIG. 16), for moving forward the pillar 36' (carrying the toolholders 17), towards the cutting face 24, for a distance equal to the forward step chosen. For this end, all jacks of carriage 2 are released, except the jacks 7 and 8 of pillar 36. The pivoting of carriage 2 about the pillar 36 is then carried out by means of jacks 10 bearing on the framework 1 which is maintained still in the gallery 4 by means of its jacks 3 applied against roof 5 and floor 6. During this pivoting of the carriage 2, the superposed arms 11 may continue to be rotated around their pillar 36, as far as their respective toolholders 16 have ended their respective operational cycles.

After the carriage 2 has been pivoted as above described, in sense of the arrow A (FIG. 16), it is maintained still in this new

position by means of the jacks 10 and eventually jacks 7 and 8 and/or jacks 49. The superposed arms 12 are then swung from inside towards outside for their toolholders 17 carrying out a new operational cycle during which they cut each another crescent-shaped rock "chip" in the cutting face 24. This other rock "chip" has been indicated at 50, on FIG. 16.

The jack 8 of pillar 36 is released and jack 8 of pillar 36' is applied against the roof 5 of the gallery 4.

While the toolholders 17 of superposed arms 12 are carrying out the new operational cycle and after the toolholders 16 of superposed arms 11 have ended their own operational cycle and are thus directed inside, the carriage 2 is pivoted in sense of the arrow B (FIG. 16) around the pillar 36' (carrying the toolholders 17) for moving forward the pillar 36 (carrying the toolholders 16) on a distance equal to the forward step chosen.

The toolholders 16 are thus in an adequate position for carrying out a new operational cycle during which they cut respectively new rock chips in the cutting face 24 of the gallery 4.

When the jacks 10 have reached the dead-center, after both pillars 36 and 36' have been alternately moved several times forwardly in the gallery 4, the carriage 2 is maintained still in the gallery, by means of its jacks 7, 8 and 49 (FIG. 17). The upper jacks 3 of framework 1 are then released and the framework is moved towards the carriage 2, by means of jacks 10.

The preceding description of the process according to the invention for digging a gallery 4, by means of the machine of FIGS. 12 and 13 adapted as in FIG. 15 has related to the case in which the toolholders 16 and 17 act on the cutting face during only one half of their operational cycle, i.e. as they are moved from the central zone of the gallery as far as the lateral walls 22 and 23 of this gallery.

It is evident that the process may also be adapted to the case in which the toolholders act on the cutting face 24 during their entire operational cycle, i.e. on the one hand while they are displaced from the central zone of the gallery 4 as far as the lateral walls 22 and 23 of the same, the toolholders passing continuously along the cutting face 24 of the gallery and, on the other hand, while they are displaced from the lateral walls as far as the central zone. In this case, the aforesaid successive pivotal displacements of the carriage 2 alternately around the pillars 36 and 36' in sense of the arrows A and B (FIGS. 16 and 17) are carried out after each half of an operational cycle of the toolholders.

In this process according to the invention, adapted to the machine of FIGS. 12 and 13, the aforesaid forward step may be chosen at any time — i.e. for each forward displacement of a pillar — according to the actual rock cutting resistance.

The machine shown on FIGS. 12 and 13 is particularly well adapted for rectifying or modifying its directional course with reference to the axis of the cut part of the gallery. For this end, the bearers 7 and 48 are preferably jacks.

It is notably easy to modify the declivity or gradient of the gallery 4. For this end, the framework 1 is immobilized in the gallery 4 by applying its jacks 3 on roof 5 and floor 6. The jacks 8 and 49 of carriage 2 are released and the jacks 10 are then worked in such a manner that the upper jack 10 are differently worked than the lower jacks 10 for pivoting the carriage 2 simultaneously on its two bearers 7 or on its two bearers 48, forwardly or rearwardly.

During this pivoting of carriage 2, bearers 7 or 48 about which this carriage is pivoted are worked for adjusting the position of the toolholders 16 and 17 relative to the roof 5 and the floor 6 of the gallery 4.

An auxiliary framework 44 similar to that which has been described hereabove, in case of the machine of FIGS. 1 and 2, may be situated behind the framework of the machine.

FIG. 18 shows a further form of embodiment of the machine of this invention.

According to this form of embodiment, the machine comprises a framework 1 whereon are mounted two carriages 52

and 53 for being able to slide individually relative to this framework 1, the carriages 52 and 53 being constantly parallel to each other during their respective slide movements. The framework 1 is equipped with jacks 3, 13 and 54 for ensuring its immobilization in the gallery 4 which is in process of being cut.

Each of the carriages 52 and 53 is provided with a lower bearer (not shown) adapted for supporting the carriage on the floor 6 of the gallery 4. This bearer is similar to the aforesaid bearer 7 of the machine of FIGS. 12 and 13; it is preferably a jack. Each carriage 52, 53 is further provided with an upper jack 8 which is advantageously straight above the bearer and which is adapted for maintaining the carriage still in the gallery 4, when applied against the roof 5 of the gallery.

Carriages 52 and 53 are connected to the framework 1 by jack 10.

On carriage 52 is mounted a vertical pillar 36 and, on carriage 53, another vertical pillar 36'. These pillars are respectively in prolongation of the aforesaid bearers and jacks of the carriages.

Two superposed arms 11 are mounted on the pillar 36 of carriage 52, around which they can pivot. Two similar superposed arms 12 are mounted on the pillar 36' of carriage 53, around which they can pivot.

Each arm 11 carries one or several toolholders 16 provided with cutting tools 20. Each arm 12 carries also one or several similar toolholders 17.

The arms 11 and 12, the tool-holders 16 and 17 and the cutting tools 20 may be similar to those described hereabove, in the case of the machine of FIGS. 12 and 13. Notably, the length of each of the arms 11 and 12 may be greater than one half of the distance between the axis of both pillars 36 and 36' which are parallel to each other. Thus, the crescent-shaped areas 25 cut in the cutting face 24 by the toolholders 16 partially overlap the similar areas 26 cut in the cutting face 24 by the toolholders 17.

In such embodiment, it is necessary to provide means — for example limit switches — for homologous arms 11 and 12 assuming positions relative to one another, similar to those hereabove described in case of the machine of FIG. 15.

The machine of FIG. 18 is well adapted for the cutting of the gallery 4 with the process according to the invention.

In this connection, the case will be considered in which the toolholders 16 and 17 act on the cutting face 24 of the gallery 4, only during one half of their operational cycle.

According to the process of this invention, after the toolholders 17 carried by carriage 53 have ended their operational cycle and are in the central zone of the gallery and before they begin a new operational cycle, the jack 8 and eventually the jack 7 of carriage 53 are released. This carriage 53 is then made to slide relative to the framework 1 by means of its jack or jacks 10, for moving forward the pillar 36' (which is carried by the carriage 53), on a distance equal to the forward step chosen. During the sliding displacement of the carriage 53 relative to the framework 1, the latter is maintained still in the gallery 4, by means of its jacks 3, 13 and 54. During the sliding displacement of the carriage 53 on the framework 1, the superposed arms 11 continue to pivot around their pillar 36, until their respective toolholders 16 have ended their operational cycle.

After the carriage 53 has slide on the above mentioned distance towards the cutting face 24, it is maintained still in its new position by means of its jacks 10 and 8 and its bearer 7. The superposed arms 12 carried by the carriage 53 are then made to pivot for each of the toolholders 17 carried respectively by these superposed arms 12 carrying out a new operational cycle during which it cuts a new rock "chip" in the cutting face 24. This new rock "chip" is represented at 55 in FIG 15.

While the toolholders 17 are carrying out this new operational cycle and after the toolholders 16 have ended their operational cycle, the jack 8 and eventually the jack 7 of the carriage 52 are released and this carriage 52 is made to slide

relative to framework 1, by means of its jack or jacks 10, for moving forward the pillar 36 carried by the carriage 52, on a distance equal to the forward step chosen. The toolholders 16 of this carriage 52 are thus in an adequate position for each carrying out a new operational cycle and cutting a new rock "chip" in the cutting face 24 of the gallery 4.

When the jacks 10 have reached the dead-center, after both carriages 52 and 53 have been alternately made to slide forwardly several times relative to the framework 1, these carriages are maintained still in the gallery 4, by applying their jacks 8 against the roof 5 of the gallery and their bearers 7 on the floor 6. The jacks 3, 13 and 54 of framework 1 are then released and this framework is moved towards the carriages 52 and 53, by means of the jacks 10.

In the preceding description of the process according to the invention, for the digging of a gallery 4 by means of the machine of FIG. 15, the case has been considered in which the toolholders 16 and 17 act on the cutting face 24 during only one half of their operational cycle.

It is evident that this process may also be adapted to the case in which the toolholders 16, 17 act on the cutting face 24 during their entire operational cycle, i.e., on the one hand while they rotate from the central zone of gallery 4 as far as the lateral walls 22 and 23, the toolholders passing them continuously along the cutting face 24 and, on the other hand while they rotate from these lateral walls as far as the central zone.

In this type of working, the successive sliding displacements of the carriages 52 and 53 relative to the framework 1, towards the cutting face 24 are carried out after each half of an operational cycle of the toolholders.

In the process according to the invention, adapted to the machine of FIG. 18, the aforesaid forward step may be chosen at any time for the forward displacement of a carriage 52, 53, according to the actual rock cutting resistance.

An auxiliary framework 44 similar to that which has been described hereabove may also be provided behind the framework 1 of the machine.

The machine shown on FIG. 15 is further adapted for being able to pivot as a whole around one single axis corresponding to the axis of the said jack 13. For this hand, this jacks and the corresponding bearer on the floor 6 are preferably connected to the framework 1 by bearings. Thanks to this advantageous particularity of the machine of FIG. 18, it is possible to lightly rectify or modify the directional course of the machine through the gallery.

In the case of the digging of a gallery through a bedding formation, the layers or strata of which are approximately parallel to the floor and roof of the gallery, the "pumping effect" produced in these layers or strata by successively wedging and releasing the jacks 7 and 8 can be detrimental for the solidity of the gallery.

The form of embodiment partially and diagrammatically represented in FIG. 19 is particularly well adapted for avoiding such a prejudicial "pumping effect".

The machine of FIG. 19 comprises a framework 1 provided with bearers (not shown) for its upholding upon the floor 6 and with two pairs of opposed jacks 67 adapted to be applied against the lateral walls 22 and 23 of the gallery 4 for immobilizing the said framework 1.

On the framework 1 are slidably mounted two carriages 52 and 53 connected each to the framework 1 by articulated driving means (not shown). These means may for example be jacks similar to jacks 10 of the machines hereinbefore described. They are adapted for being able not only to drive each carriage relative to the framework 1, but also to immobilize this carriage on this framework while its toolholder or toolholders act on the cutting face 24 of the gallery. Each of these two carriages 52, 53 is rearwardly provided with a section 68 slidably mounted in a corresponding shaped slideway provided through the framework 1. The carriages 52 and 53 are further connected to the framework 1 by means adapted to make these carriages individually slide on the framework 1.

These means, not shown on FIG. 19, may be hydraulic jacks or a rack and pinion.

Each carriage 52, 53 is further provided with a bearer (not shown) adapted to uphold this carriage upon the floor 6 of the gallery.

The aforesaid bearers of framework 1 and carriages 52 and 53 are preferably jacks.

Carriage 52 carries one or several — for example two — superposed turrets 69 able to swing about a common swinging axis substantially parallel to the axial plane of the machine.

On each turret 69 is fixed an arm 11 disposed transversally to the swinging axis of turret 69 and carrying, at its end, a tool-holder 16 equipped with tools 20.

Carriage 53 carries also one or several superposed turrets 70 similar to turrets 69 and able to swing about a common swinging axis substantially parallel to the swinging axis of turrets 69.

On each turret 70 is fixed an arm 12 similar to arm 11 and similarly disposed on the turret. This arm 12 carries, at its end, a tool-holder 17, similar to toolholder 16.

In the machine of FIG. 19, the toolholders 16 and 17 and tools 20, as well as the positions of these tools on the toolholders and of the latter on arms 11 and 12 are similar to machines of FIGS. 1, 2, 12, 13 and 18.

The machine of FIG. 19 is further provided with means adapted to immobilize individually each carriage on the framework 1, transversally to the sliding direction Z of the carriage on the framework. These means may be advantageously jacks 71 fixed on the framework 1 and able to be wedged against sections 68 of the carriages.

Thus, in the machine of FIG. 19, for moving a carriage on framework 1, towards the cutting face 24 of the gallery, the jacks 71 adjacent this carriage are released and the latter is made to slide on framework 1, over a length equal to the cutting step chosen, the framework 1 being maintained immobilized in the gallery by jacks 67 applied against the lateral walls 22 and 23. As the carriage has been moved forward over the length, it is immobilized on the framework 1 by its aforesaid driving means and by wedging the pistons of jacks 71 against the section 68 of this carriage.

For allowing forward displacement of the framework 1 through the gallery 4, notably as the aforesaid driving means and/or the sections 68 in their slideways have come completely off, the jacks 67 are released as well as jacks 71 and the framework 1 is made to slide on the floor 6 towards the carriages 52 and 53 by means of the driving means. During this forward displacement of framework 1 relative to carriages 52, 53, these carriages are maintained still on the floor 6 of the gallery, generally due to their own weight.

In view of increasing the immobilization of the carriages 52 and 53 in the gallery, notably in case of a sloping gallery, these carriages may be provided with jacks adapted to be temporarily wedged against the roof 5 or both opposed walls 22 and 23 of the gallery. The use of these jacks does not provoke the above mentioned detrimental "pumping effect": indeed, these jacks are used only temporarily for moving forward the framework 1, and not for retaining the carriages 52 and 53 during the operational cycles of their toolholders. Further, the pressures of these jacks against the roof 5 of the lateral walls 22 and 23 of the gallery is much less than the pressure which is necessary for retaining the carriages, in case of the machine of FIG. 18, for example, as their toolholders act against the cutting face 24 of the gallery 4.

For allowing a pivotal movement of the machine inside the gallery, the framework 1 is provided, substantially along its axial plane, with a jack 72 parallel to the swinging axis of turrets 69 and 70 and adapted to be applied against the roof 5 of the gallery. In prolongation of this jack 72, the framework is provided with another jack adapted to be applied against the floor 6 of the gallery 4.

For pivoting the machine inside the gallery, these last jacks are applied respectively against the roof and the floor of the gallery and the jacks 67 are released. The framework 1 can

thus be pivoted about the axis of jack 72, by means, for example, of a jack connecting this framework 1 to an auxiliary framework (not shown) immobilized in the gallery, behind framework 1.

The pivoting of the machine parallel to its axial plane may be executed as hereinbefore described for the other embodiments of the machine according to the invention. 5

In a modified variation of the form of embodiment of FIG. 19, the framework is mounted on a caterpillar-tractor adapted to progress on the floor 6 of the gallery. Jacks may be provided for adjusting laterally and longitudinally the inclination of the framework 1 on this caterpillar-tractor. 10

Each of the hereabove described embodiments of the machine of the invention has been supposed comprise two parallel swinging axis, i.e. one axis for superposed arms 11 and one axis for superposed arms 12. It is evident that the machine may comprise more than two parallel swinging axis, for example three or four swinging axis, according to the width of the gallery to be cut. These swinging axis are preferably disposed substantially in a same plane transverse to the axial plane of the machine. 15

In case of machines similar to those of FIGS. 1 and 2 or 12 and 13, the arms corresponding to all the swinging axis are mounted on a single carriage 2. 20

In case of machines similar to those of FIGS. 18 and 19, the arms are mounted on as many carriages like 52 or 53 as they are parallel swinging axis. 25

Further, about each swinging axis, the carriage may be provided with one or more superposed arms, for example two, three or four superposed arms, according to the height of the gallery to be cut. 30

About each swinging axis, the superposed arms may have a same length as in the case of the machines hereabove described or, on the contrary have a different length. The toolholders of these superposed arms may also, if necessary for the rock cutting resistance, be of different sizes and/or configuration. 35

About each swinging axis, the superposed arms may be mounted around a common pillar such as pillars 36 or 36' of the machines of FIGS. 1,2,12,13 or 18. They can also be mounted each on an individual turret such as turrets 69 and 70 of the machine of FIG. 19. The arms may be disposed perpendicularly or, on the contrary oblique to their swinging axis. 40

Further, about each swinging axis, the superposed arms may be adapted to swing individually or, on the contrary, they may be coupled to one another by adequate torque transmission devices. In particular, all the superposed arms able to swing about a common axis may be attached to one another and their respective toolholders coupled to one another as shown 50 on FIG 8.

In the hereabove described forms of embodiment of the machine of this invention, each toolholder has been supposed mounted on its arm, with its rotation axis parallel to this arm. It is evident that in case of rotatable toolholders with cutting 55 discs, as represented on FIGS. 3 and 4, the position of each toolholder on its arm could also be such that the toolholder's rotation axis, while being parallel to an axial plane of this arm, be oblique on this arm.

In the place of the rotatable toolholders with which the 60 machines described hereabove are equipped, these machines may also be equipped with toolholders which are fixed on their respective arms.

Moreover, the cutting discs 20 may be replaced by other tools, for example picks, rotatable cutters, compressed air 65 tools, hydraulic or pyrometric means, etc..

The present invention is not limited to the forms of execution illustrated, an many modifications may be made in the shape, the arrangement and the construction of certain of the elements used in carrying it into effect, on condition that the 70 said modifications do not conflict with the aim of any of the following claims.

What I claim is:

1. A machine for digging underground galleries, comprising: a framework;

a toolholder;

means for moving the framework forward in the gallery; at least two superposed pairs of arms connected to the framework and adapted to swing about two substantially parallel axes transverse to the forward movement of the framework, each arm being provided with a toolholder mounted for rotation at its extremity so that the toolholder can cut through the cutting face of the gallery when its respective arm swings about its axis from inside towards outside with regard to the framework, each arm plus its toolholder having a length, measured from the swinging axis of its arm, greater than half the distance between both swinging axes, but less than the distance; at least a pair of carriages connected to the framework and supporting respectively both arms of each pair of arms, the carriages being adapted to slide on the framework, parallel to the forward movement of the framework, whereby both arms of the pair are individually movable forwardly and rearwardly on the framework; means for individually driving both carriages forwardly and rearwardly on the framework; and

means for making both arms of the pair swing individually about both axes, from a position for which the arms are turned inside, with their respective toolholders in the rear of the intersection line of their respective circular displacements about the axes, of a length at least equal to the cutting step, towards a position for which these arms are turned outside, the toolholder of each arm cutting through the face of the gallery only when it is swung from inside towards outside, whereby it is possible to use the machine continuously.

2. A machine for digging underground galleries, comprising: a framework;

a toolholder;

means for feeding the framework forward in the gallery; at least a pair of superposed pairs of arms connected to the framework and adapted to swing about two substantially

parallel swinging axes transverse to the forward movement of the framework, each arm being provided with a toolholder mounted for rotation at its extremity, so that the toolholder can cut through the cutting face of the gallery when its respective arm swings about its swinging axis from inside towards outside with regard to the framework, each arm plus its toolholder having a length, measured from the swinging axis of its arm, greater than half the distance between both swinging axes, but less than the distance;

means for individually immobilizing both swinging axes with respect to the framework;

a single carriage articulated to the framework and supporting the arms;

articulated driving means connecting the carriage to the framework, for producing alternative rotations of the carriage successively about one of both axes and about the other one, this axis being first immobilized, whereby both axes can be alternately displaced forward of a length substantially equal to the cutting step, and

means for making both arms of the pair of arms to swing individually about both axes, from a position in which the arms are turned inside, with their respective toolholders in the rear of the intersection line of their respective circular displacements about the swinging axes, of a length at least equal to the cutting step, towards a position for which these arms are turned outside, the toolholder of each arm cuts through the face of the gallery only when it is swung from inside towards outside, whereby the machine can function continuously.

3. A machine for digging underground galleries comprising: a framework;

a toolholder;

means for feeding the framework forward in the gallery; at least a pair of arms connected to the framework and adapted to swing respectively about two substantially parallel swinging axes transverse to the forward move-

- ment of the framework, each arm being provided with a toolholder mounted for rotation at its extremity, so that the toolholder can cut through the cutting face of the gallery when its arm swings about its swinging axis from inside towards outside with regard to the framework, each arm plus its toolholder having a length, measured from the swinging axis of this arm, greater than half the distance between both swinging axes, but less than the distance;
- means for individually and alternately displacing both swinging axes forward to a length substantially equal to the cutting step;
- means for individually driving both carriages forward and rearward on the framework; and
- means for making both arms of the pair of arms to swing individually about both axes, from a position for which the arms are turned inside, with their respective toolholders in the rear of the intersection line of their respective circular displacements about the swinging axes, of a length at least equal to the cutting step, towards a position for which these arms are turned outside, the toolholder of each arm cuts through the face of the gallery only when it is swung from inside towards outside, whereby the machine can work continuously.
4. A machine for digging underground galleries comprising: 25
a framework;
a toolholder;
means for feeding the framework forward in the gallery;
at least a pair of arms connected to the framework and adapted to swing respectively about two substantially 30 parallel swinging axes transverse to the forward movement of the framework, each arm being provided with a toolholder mounted for rotation at its extremity, so that the toolholder can cut through the cutting face of the gallery when its arm swings about its swinging axis from inside towards outside with regard to the framework, each arm plus its toolholder having a length, measured from the swinging axis of the arm, up to half the distance between both swinging axes;
- an additional digging device provided on the framework 40 between both swinging axes, and adapted for cutting through the face of the gallery in the mediane zone of this gallery;
- means for moving forward simultaneously both swinging axes, a length equal to the cutting step, and
- means for moving both arms to swing simultaneously and symmetrically about the axes, from a position in which the arms are turned inside, with their respective toolholders in the rear of the extreme forward position achieved by the additional digging device in front of the framework, of a length at least equal to the cutting step, 50 towards a position for which these arms are turned outside, the toolholders of both arms of each pair cut simultaneously through the face of the gallery, only when they are swung from inside towards outside, whereby it is possible to use the machine in a continuous manner.
5. A machine as claimed in claim 4, wherein the means for moving simultaneously both swinging axes forwardly include: 55
a carriage slidably mounted on the framework, parallel to the forward displacement of the framework, the carriage supporting the arms, and
means for driving the carriage forward and rearward on the framework.
6. A machine as claimed in claim 4, wherein each rotatable toolholder has its rotation axis substantially parallel to the arm on which it is carried, and is provided with rotatable cutting discs mounted on the toolholder in such a manner that the rotation axes of the discs constitute substantially a generatrix of a conical surface the apex of which is approximately on the rotational axis of the toolholder, beyond the swinging axis of the arm carrying the toolholder, the discs acting on the cutting face of the gallery approximately tangentially to their circular courses about the swinging axis of the arm carrying the toolholder.
7. A machine as claimed in claim 6, wherein the cutting discs of each toolholder are situated in the peripheral part of the toolholder and are contingently distributed in at least two substantially coaxial stepped areas.
8. A machine as claimed in claim 7, wherein the offset of each cutting disc of one area with respect to the discs of the next area is adjustable parallel and transverse to the rotation axes of the discs.
9. A machine as claimed in claim 8, further including a case removably inserted into a corresponding hollow casing of the toolholder and mounting a cutting disc, a removable gauged plate being inserted between the case and the bottom of the casing in order to adjust offset, parallel to the rotation axis of the disc.
10. A machine as claimed in claim 9, wherein the casing has a part oblique with respect to the rotation axis of the disc, the oblique part being removably applied against a corresponding oblique part of the toolholder, the casing being displaceable on the toolholder, parallel to the oblique parts, for adjusting the offset of the disc simultaneously parallel and perpendicular to the rotation axis of the disc.
11. A machine as claimed in claim 4, further including an evacuating means for rubble cut having:
- a pair of circular bins disposed respectively around both swinging axes, at the level of the floor of the gallery;
  - a sloping plane member in front of each circular bin, for allowing rubble cut to pass from the floor of the gallery into the bin;
  - at least one oblique scraper on each arm adjacent to the floor of the gallery, for pushing the rubble cut towards the bin;
  - a conveyor in the vicinity of each bin, for conveying the rubble cut from this bin towards the rear of the framework;
  - at least one ramp in each bin, in the vicinity of its contiguous conveyor, for allowing the rubble cut to pass from the bin onto the conveyor, and
  - a scraping tool displaceable inside each bin, in rotary reciprocating movement about the swinging axis corresponding to the bin, whereby the rubble cut can be pushed from this bin onto the contiguous conveyor, along the ramp of the bin.
12. A method for cutting underground galleries of substantially rectangular section by using a machine having:
- a framework;
a toolholder;
means for feeding the framework forward in the gallery;
at least a pair of arms swingable on the framework respectively about two substantially parallel swinging axes transverse to the forward movement of the framework, and provided each with a toolholder mounted for rotation at the extremity of the arm, so that the toolholder can cut through the cutting face of the gallery when its arm swings about its swinging axis from inside towards outside with regard to the framework, each arm plus its toolholder having a length, measured from the swinging axis of this arm, greater than half the distance between both swinging axes, but less than the distance, the method comprising the successive steps of:
- moving one arm of the pair of arms to swing about one of the swinging axes, successively first from inside towards outside, so that the toolholder of this arm makes one cut through the face of the gallery, and then from outside towards inside without acting on the cutting face;
- maintaining the one arm still about its swinging axis, and moving forward the axis towards the face of the gallery, on a distance substantially equal to the cutting step chosen, and
- during this forward movement, continuing to move the other arm of the pair so as to swing about the other swinging axis, swinging successively first from inside towards outside, so that the toolholder of this arm makes one cut through the face of the gallery, and then from outside towards inside without acting on the cutting face.
